JOHN J. EGAN AND EUGENE GREGOR, OF NORTHAMPTON, MASSACHUSETTS, ASSIGNEES
TO McCALLUM HOISERY COMPANY, OF NORTHAMPTON, MASSACHUSETTS, A COR-
PORATION OF MASSACHUSETTS.

PLATING ATTACHMENT.

Application filed April 20, 1925. Serial No. 24,408.

Our invention relates to stocking knitting machines and has particularly to do with the production of what is known as plated wear, that is, fabric made by laying two threads in the needles at the same time, one above the other, and otherwise knitting the same as if a single thread were used, with the result that in the finished fabric one thread appears at the face and the other at the back, and if the threads are of different colors as they usually are, the front and the back of the fabric are of different colors. In making this sort of fabric it has been possible by a proper shaping of the dividers or sinkers between appropriate needles to produce at those points vertical stripes in which the color at the back is brought to the front and vice versa, as shown for instance in the patent to Tebbutt, No. 1,145,522.

The principal object of our invention is to provide means whereby the relative positions of the threads may be reversed, according to a predetermined plan, so that after a portion of fabric has been knitted with one color on top, the threads may be reversed, and a portion knitted with the other color on top, and the color which was on the face at the back. In this way a horizontally striped plaited effect may be obtained with the colors alternating as desired.

With this object in view our invention consists in the construction, combination and arrangement of parts herein described and claimed, and illustrated in the accompanying drawings. For convenience we have shown the invention as applied to a straight knitting machine of the general type known as a Cotton machine, in which the fabric of the stocking is knit as a web, suitably shaped and narrowed, and the stocking is then made up by stitching the edges of the web together. Since this type of machine is well-known, we have shown in the drawings only such parts as are necessary for an understanding of this invention, thus avoiding confusion in the drawings and making it possible to set forth the invention more simply and clearly.

In these drawings, in which similar reference characters designate corresponding parts in all views:

Figure 1 is a partial transverse section of

a knitting machine, showing in elevation the parts embodying the invention as applied thereto;

Fig. 2 is a partial front view showing the pattern chain, and the cam levers actuated thereby;

Fig. 3 is a partial front view of the machine with parts broken away, showing the parts of the invention as applied to the friction and thread carrier rods;

Fig. 4 is a perspective view showing in semi-diagrammatic form the relative position of the friction arms and the lugs and forks on the thread carrier rods;

Fig. 5 is a detail partly in section showing the relation between the friction arm 15 and the cooperating carrier rod lugs, viewed from the end of the machine;

Fig. 6 is a view similar to Fig. 5, showing the friction arm 13 and the forks on the carrier rods engaged thereby;

Fig. 7 shows a simple form of fabric as made in accordance with this invention; and,

Fig. 8 shows another type of fabric that can be made in accordance with the invention.

Referring to the drawings, we have shown some of the essential parts of the machine, namely, the framework 1 and the rack 2 in which a number of carrier rods, including the carrier rods 3 and 4 are longitudinally slidable; a friction rod 5 supported in the usual manner upon a suitable slide 6; the needles 7, dividers or sinkers 8; and lace points 9 supported in the usual manner by arms 10. The carrier rods 3 and 4 are provided with thread guides 11 and 12, respectively, in the usual manner.

As is well-known, in machines of this type there is usually a friction arm 13 for each of the several thread-carrier rods as illustrated by the rods 3, 4, these friction arms being adapted to be thrown back out of the way when the corresponding carrier rod is not in use; or thrown forward as illustrated to engage a suitable fork upon the carrier rod when it is desired to actuate that rod. For instance, the friction arm 13 would normally be adapted to engage the fork 16 upon the carrier rod 4; or to be disengaged therefrom and thrown back out of the way; but this friction arm 13 would be shaped for this

particular purpose, and would not be used in connection with any other carrier rod than the rod 4.

In carrying out the present invention, it is desired that at times the friction arm 13 may actuate the carrier rod 4; but at other times it is desired that the said friction arm actuate the carrier rod 3. To this end the carrier rod 3 is provided with a fork 17 which extends upwardly and inwardly of the machine to a point approximately above the fork 16; and the friction arm 13 may if desired be provided with an extension 18 (Fig. 6), so that when the friction arm 13 is raised sufficiently to become disengaged from the fork 16, a slight further upward movement causes it to engage the fork 17 (Fig. 1), which is fixed to the carrier rod 3 in the same longitudinal position as the fork 16 upon the carrier rod 4.

Referring to the detail in Fig. 6 it will be seen that when the friction arm 13 is in the lower position, it engages the fork 16 of the carrier rod 4 as shown in full lines, and when in the upper position it engages the fork 17 of the carrier rod 3, as shown in dash lines. Thus when the friction arm 13 is in the full line position as shown in Figs. 4 and 6, the carrier rod 4 is actuated thereby, and when the friction arm 13 is in the dash line position of Fig. 6 the carrier rod 3 is actuated thereby.

The movement of the friction arm 13 from one position to the other is effected by means of the mechanism shown particularly in Figs. 1 and 2 for actuating the arm 19 which is keyed to the friction rod 5, so as to rotate the friction rod 5 through an arc sufficient to take the friction arm 13 from engagement with one fork, 16 or 17, to engagement with the other.

Inasmuch as it is desired that the movement from one position to the other be effected from time to time in accordance with a predetermined plan, the motion is preferably obtained from a pattern chain 20. This chain may be driven by a sprocket wheel 21, which is moved ahead a notch with each reciprocation of the friction rod 5 in the well-known manner (the power connections not being shown), the other end of the chain being mounted upon a small adjustable sprocket 22 held in position by a spring 23 extending to and attached to the frame of the machine at a suitable place, in the usual manner. The pattern chain is provided with lugs or cams 24, 25 which are preferably arranged in two rows so as to lift the cam levers 26, 27 which are arranged side by side and carried by a pin 28 mounted upon the frame 1.

Arranged to be actuated by the cam levers 26, 27 and to transmit the motion therefrom to the rear of the machine are a pair of levers 29, 30, actuated by the cam levers 26,

27 respectively. These levers are suitably fulcrumed upon a pin 31 carried by a bracket 32 from the frame 1.

Mounted upon the fixed rod 33 of the machine is a lever 34 extending in an up and down direction, at the lower end of which is a pin 35 adapted to be engaged by the levers 29 and 30 in order that the lever 34 may be moved backward or forward by the levers 29 or 30. To this end the lever 29 has a downwardly turned end 36 and the lever 30 has an upwardly turned end 37. The end 36 of the lever 29 extends beyond the pin 35 and rests on the far side thereof, so that when the front end of the lever 29 is pushed upwardly by the cam lever 26, the end 36 is brought downward to the position shown in Fig. 1, thus drawing the pin 35 forward and moving the lever 34 correspondingly to the position shown. When the lever 30 is moved upward by the cam lever 27, the end 37 thereof is brought downward from the position shown in full lines, and pushes the pin 35 backward, at the same time causing the end 36 of the lever 29 to rise to its other extreme position, and throwing the lower end of the lever 34 backward and the upper end forward.

At the upper end of the lever 34 there is hinged a hook member 38, which is prevented from dropping below the desired position by a lug 39 upon the lever 34, this lug holding the hook member 38 so that the hook 40 thereof is in position to be engaged by a tapered pin 41 carried by the arm 19 on the friction rod 5, when the friction rod is at the end of its stroke.

Thus at the end of a stroke of the friction rod 5, the parts are in position as shown so that they may be actuated by one of the cams 24, 25 to throw the friction rod from one position to the other, and thus cause the friction arm 13 to disengage one of the forks 16, 17 and to engage the other as desired.

The friction rod 5 carries a pair of additional friction arms 14, 15, arranged to move between two positions simultaneously with the movement of the friction arm 13. For cooperation with the friction arms 14, 15 the carrier rods 3 and 4 are provided with lugs 42, 43 respectively for cooperation with the friction arm 14; and 44, 45 respectively for cooperation with the friction arm 15. The lugs 42, 43 on the carrier rods 3, 4 respectively are disposed thereon in the same relative longitudinal position; and the same is true of the lugs 44, 45. These lugs 42, 44 on the carrier rod 3 and the lugs 43, 45 on the carrier rod 4 are thus spaced apart the same distance; and this distance is less than the distance between the friction arms 14, 15, the lugs being between the friction arms, so that after the parts have completed their travel to the right they are in the relative positions shown in Fig. 4. On the next

stroke to the left, the friction arm 14 travels the distance from the position shown to the position of the lugs 42, 43 before it picks up one or other of these lugs to move the 5 carrier rod to which that lug is attached; and in starting a stroke to the right, the friction arm 15 has to travel the same distance before it picks up one of the lugs 44, 45.

The heads 46, 47 of the friction arms 14, 10 15 are so shaped that when the friction arms are in their lowest or forward position, as shown in Fig. 4 and in full lines in Fig. 5, they engage with the lugs 42, 44 of the carrier rod 3, and clear the lugs 43, 45 of the 15 carrier rod 4; and when the friction arms 14 and 15 are in their upper or rear position (dash lines, Fig. 5), they are in line to engage the lugs 43, 45 of the carrier rod 4 and clear the lugs 42, 44 of the carrier rod 3.

20 It will now be apparent that in the upper or rear position of the friction arms (Fig. 1) the friction arm 13 engages and actuates the carrier rod 3 through the fork 17, while the carrier rod 4 is being reciprocated by means 25 of the friction arms 14, 15 acting through the lugs 43, 45; and when the friction arms are thrown to their forward or lowermost positions (Fig. 4) the conditions are reversed and the carrier rod 4 is actuated through 30 the friction arm 13, engaging the fork 16, while the carrier rod 3 is actuated by means of the friction arms 14, 15 cooperating with the lugs 42, 44.

Thus it will appear that whichever of the 35 carrier rods, 3, 4 is actuated by the friction arm 13, that rod travels with the friction rod 5, whereas the other carrier arm is actuated through the friction arms 14 and 15 and lags behind while the friction arm 14 or 15 travels the distance from its position 40 at the end of the stroke to the position of the lugs at the end of the stroke, so that the thread carrier on this rod lags behind the one driven by the friction arm 13, and lays 45 the thread carried thereby on top of the thread carried by the thread carrier on the rod actuated by the friction arm 13.

While in describing the invention the operation has been pointed out to a considerable extent, it may be well to summarize the 50 operation of the machine as follows:

Assume that the parts are as shown in Fig. 1, in which the friction arms 13, 14, 15 are in raised position (dash lines, Figs. 5 and 6), so that the friction arm 13 is in engagement with the fork 17, so as to actuate the carrier rod 3 and lay the thread carried by this rod, which for convenience we may assume is a blue thread, first, in the 60 needles, while the thread carried by the carrier rod 4, which for convenience we may call a brown thread, lags behind the blue thread, the carrier rod 4 being actuated through the lugs by the friction arms 14, 15, so that the brown thread will show up 65

on top as the fabric is being knit. In this position the arm 19 is in its back position, and the lever 34 and the hook levers 29 and 30 are in the positions shown in Fig. 1.

So long as these parts remain undisturbed, 70 the knitting action of the machine goes on with the friction rod reciprocating back and forth, carrying with it the thread carrier rod 3 with the blue thread which is laid in the needles by the thread carrier 11; and the 75 thread carrier rod 4 follows in each direction, when picked up by the arm 14 or 15, a short distance behind the rod 3, so that the carrier 12 lays the brown thread in on top of the blue thread after it, and the fabric 80 is knit with the brown thread showing up on top and the blue thread underneath.

Let us assume that it is desired to knit a fabric such as that shown in Fig. 7 in which 85 alternating horizontal stripes of equal width are desired.

In this case the cams 24, 25 on the pattern chain 20 are set equal distances apart, first one in the outer row, and then one in the inner row. The knitting of the first row 90 50 showing brown on top will continue until the desired width is obtained, at which time the cam 25 comes into contact with the depending portion of the cam lever 27, raising the cam lever 27, thus raising the end of the 95 lever 30 in contact therewith, and bringing the end 37 downward, thus pushing the pin 35 and the lower end of the lever 34 backward, and bringing the upper end of the lever 34 forward so that the hook member 100 38, in engagement with the pin 41 upon the friction rod 5 rotates the friction rod 5 sufficiently to bring the friction arms from their upper position (Fig. 1) to their lower or forward position (Fig. 4). The movement 105 of these levers is of course timed to take place at the end of a stroke of the friction rod while the pin 41 is in engagement with the hook 40.

This brings the friction arm 13 into contact with the fork 16 on the carrier rod 4; and brings the friction arms 14 and 15 into line for engagement with the lugs 42, 44 on the carrier rod 3; so that the carrier rod 4 will now travel with the friction rod 5 and 110 the brown thread will be laid in first; while the carrier rod 3 will now lag behind until the lugs thereof are picked up by the friction arm 14 or 15 according to the direction of travel, and the blue thread will be laid in on 115 top of the brown thread, and as the fabric is formed the blue thread will show up on top as shown in Fig. 7 by the reference character 51.

Thus the fabric will continue to be knitted with the blue thread on top and the brown thread underneath until a cam 24 on the outer row of the pattern chain actuates the cam lever 26 and causes the aforesaid parts to resume the position shown in Fig. 1, 120 125 130

whereupon the machine commences to knit the section 52 in which the brown thread is again on top and the blue thread underneath.

The type of fabric shown in Fig. 7 is one of the simplest types that can be produced by means of this mechanism. If it is desired that the width of the stripes be greater or less, this is effected by changing the position of the lugs 24 upon the pattern chain 10 in the well-known manner; and in this way any desired width of stripe may be obtained, and any desired alternation; that is to say, the stripes need not be of equal width, but may be a long stripe followed by a short 15 stripe, and another long one, or a long stripe followed by a plurality of alternating color short stripes, and then a long stripe, etc.

An effective plaid effect may be obtained such as that shown in Fig. 8 by the use of 20 this invention in connection with the use of dividers or sinkers of the type referred to in the first paragraph hereof which have the effect of reversing the thread so as to produce a vertical stripe in plated goods. 25 When such dividers or sinkers are used in connection with the apparatus of this invention, the result is not a continuous vertical stripe of a single color, but a vertical stripe which alternates in color, so that in 30 the section where the horizontal stripe is blue the vertical stripe will be brown; and where the horizontal stripe is brown the vertical stripe will be blue, producing an effect such as that illustrated in Fig. 8.

35 The patterns shown in Figs. 7 and 8 are as stated simply illustrative of the patterns obtainable in plated wear by the use of this invention.

Having now described our invention, we 40 claim and desire to secure by Letters Patent of the United States:

1. In a stocking knitting machine the combination comprising a friction rod, friction arms thereon, thread carrier rods, each of 45 said thread carrier rods having a fork for engaging one of said friction arms to travel therewith, and lugs for engagement with said friction arms to permit the said carrier rods to lag, said friction arms, forks 50 and lugs being so arranged that when one of said friction arms is in engagement with the fork of any one of said carrier rods, the carrier rods for the following threads are actuated by the engagement of said friction 55 arms with their said lugs.

2. In a stocking knitting machine the combination comprising a slidably and rotatably mounted friction rod, friction arms thereon, thread carrier rods having forks 60 and lugs thereon, and means for rotating said friction rod to bring one of said friction arms into engagement with the fork of a selected carrier rod, and certain of said friction arms into operative position with

respect to the lugs of said other carrier rods.

3. In a stocking knitting machine the combination comprising a slidably and rotatably mounted friction rod, friction arms thereon, two thread-carrier rods each having forks and lugs thereon, the fork on one of said rods being extended past the fork on the other, whereby rotation of the said friction rod to raise the said friction arms brings said arms into engagement with the 70 said fork of one of said carrier rods and into operative position with respect to the said lugs of the other, and lowering the said friction arms brings them into engagement with the fork of the second said carrier rod 75 and into operative position with respect to the lugs of the first.

4. In a stocking knitting machine the combination comprising a slidably mounted friction rod; friction arms thereon; thread 80 carrier rods having forks and lugs thereon; said friction rod being rotatable to bring one of said friction arms into engagement with the fork of either of said carrier rods and said friction arms into operative position with respect to the lugs of the other said carrier rods; an arm fixed to said friction 85 rod; a pattern chain; lugs thereon; and means arranged to be operated by said lugs to actuate said arm fixed to said friction rod.

5. In a stocking knitting machine the combination comprising a slidably mounted friction rod; friction arms thereon; thread 90 carrier rods having forks and lugs thereon; said friction rod being rotatable to bring one of said friction arms into engagement with the fork of either of said carrier rods and said friction arms into operative position with respect to the lugs of the other said carrier rods; an arm fixed to said friction 95 rod; a pattern chain; cams thereon; levers arranged to be actuated by said cams; and a hook member arranged to be operated by said levers adapted to engage said arm fixed on said friction rod, at the end of a stroke of the rod, whereby said rod may be rotatably moved from one position to another by the action of said cams.

6. In a stocking knitting machine the combination comprising carrier rods having 110 thread guides thereon, forks and lugs thereon, a slidably and rotatably mounted friction rod, friction arms thereon for engagement with said forks and lugs and means to engage said friction rod at the end of its stroke and rotatably move it from one position to another to bring about selective engagement of said arms with said forks and lugs.

7. In a stocking knitting machine the combination comprising carrier rods having 115 thread guides thereon, forks and lugs thereon, a slidably and rotatably mounted fric-

tion rod, friction arms thereon for engagement with said forks and lugs, an arm fixed to said friction rod, a hook member adapted to be engaged by said arm at the end of a 5 stroke of said friction rod, and a lever suitably mounted on the frame carrying said hook member, whereby rotation of said friction rod from one position to another may be effected to bring about selective engagement of said arms with said forks and lugs.

8. In a stocking knitting machine the combination comprising carrier rods having thread guides thereon, forks and lugs thereon, a slidably and rotatably mounted friction rod, friction arms thereon for engagement with said forks and lugs, an arm fixed to said friction rod, a hook member adapted to be engaged by said arm at the end of a 15 stroke of said friction rod, a lever suitably mounted on the frame carrying said hook member, and means for moving said lever to effect rotation of said friction rod from one position to another according to a predetermined plan to bring about selective engagement of said arms with said forks and lugs.

9. In a stocking knitting machine the combination comprising carrier rods having thread guides thereon, forks and lugs thereon, a slidably and rotatably mounted friction rod, friction arms thereon for engagement with said forks and lugs, an arm fixed to said friction rod, a hook member adapted to be engaged by said arm at the 20 25

end of a stroke of said friction rod, a lever 35 carrying said hook member suitably mounted on the frame of said machine, said lever having laterally extending studs, hook levers in engagement with said studs, and means for operating one or other of said 40 hook levers to move the aforesaid lever and effect rotation of said friction rod from one position to another to bring about selective engagement of said arms with said forks and lugs.

10. In a stocking knitting machine the combination comprising carrier rods having thread guides thereon, forks and lugs thereon, a slidably and rotatably mounted friction rod, friction arms thereon for engagement with said forks and lugs, an arm fixed to said friction rod, a hook member adapted to be engaged by said arm at the end of a 45 stroke of said friction rod, a lever carrying said hook member suitably mounted on the frame of said machine, said lever having laterally extending studs, hook levers in engagement with said studs, a pattern 50 chain, and cams thereon adapted to actuate said hook levers to move the aforesaid lever and effect rotation of said friction rod from one position to another to bring about selective engagement of said 55 60 arms with said forks and lugs.

In testimony whereof we have signed our 65 names to this specification.

JOHN J. EGAN.
EUGENE GREGOR.
